UNITED STATES PATENT OFFICE.

BERNHARD POEHLAND, OF BROOKLYN, NEW YORK.

CELLO-REST.

1,288,179.

Specification of Letters Patent. Patented Dec. 17, 1918.

Application filed August 21, 1916. Serial No. 115,966.

To all whom it may concern:

Be it known that I, BERNHARD POEHLAND, a citizen of the United States, and a resident of Brooklyn, in the county of Kings and State of New York, have invented certain new and useful Improvements in Cello-Rests, of which the following is a specification.

The invention pertains more particularly, though not exclusively, to a combined rest and stop to be placed on the floor and adapted to receive the lower end of the leg of a cello or similar musical instrument for preventing the sliding or displacement of the instrument while the player is performing thereon.

When a cello is in use it is rested on the floor and the player is seated on a chair, and when the floor is smooth, especially when waxed, the cello is likely to slip forward along the floor and interfere with the playing.

The purpose of my invention is to provide a combined rest and stop which may be located on the floor and at a proper distance from the chair on which the performer sits and which will serve to receive the lower end of the leg of the instrument and prevent any displacement of the instrument by sliding forwardly. With the use of my invention the player is relieved from the effort of preventing the instrument from sliding forwardly, and hence can devote himself with greater pleasure and efficiency to performing on the instrument.

The invention comprises, in its preferred construction, a rest or stop to receive the leg of the instrument, a flexible tape within the rest or stop and adapted to be drawn outwardly at varying lengths therefrom, and means on the outer end of the tape for connecting the same with the leg of a chair, thereby to restrain the rest or stop against movement on the floor, means being provided within the rest or stop for locking the tape against inward reeling or outward unreeling motion while the rest or stop is in use and after the same has once been adjusted with proper relation to the chair of the performer.

The invention will be fully understood from the detailed description hereinafter presented, reference being had to the accompanying drawings, in which:

Figure 1 is a perspective view of the combined rest and stop of my invention, the

same being shown as positioned for use, a chair for the performer and a cello adjacent thereto being represented by dotted lines;

Fig. 2 is a side elevation, partly in section, 60 of the same;

Fig. 3 is a central vertical longitudinal section through the rest or stop and its contained parts, the outer portion of the tape being broken away; 65

Fig. 4 is a vertical section through the same taken on the dotted line 4-4 of Fig. 6, the section through the casing of the rest or the stop being central and longitudinal;

Fig. 5 is a corresponding section of the 70 same taken on the dotted line 5-5 of Fig. 6 so far as the interior mechanism is concerned and central and longitudinal so far as the casing of the rest or stop is involved;

Fig. 6 is a vertical transverse section on 75 a larger scale through the same taken on the dotted line 6-6 of Fig. 2, and

Fig. 7 is a horizontal section through the same taken on the dotted line 7-7 of Fig. 2, a part of the tape being broken away. 80

In the drawings, 10 designates a suitable chair for the player on a cello, 11 a cello of usual construction, and 12 the rest or stop of my invention which, as shown in Fig. 1, is adapted to receive the lower end of the 85 leg 13 of the cello and to be connected with a leg of the chair 10 by means of a tape 14 and strap or band 15 secured to the outer end of said tape.

The rest or stop 12 comprises an exterior 90 casing 16, which may be of wood, and this casing preferably has flat sides, a dome portion 17 and a rearwardly projecting tongue portion 18 which has formed in its upper surface a recess 19 which receives the lower 95 pointed end of the leg 13 of the cello. The forward or domed portion of the casing 16 is hollow and contains a closely fitting metal barrel or sleeve 20 within which is mounted, on a pin 21, a rotatable drum 22, said 100 drum being of less diameter than said sleeve and adapted to receive on its exterior a tape 14 and on its interior a clock spring 24, one end of which is connected with the pin 21 and the other with the wall of the drum 22. 105

The outer face of the sleeve 20 and drum 22 are substantially closed by a plate 25 containing a central opening for the pin 21 and also for the shank of a head 26 applied upon the outer end of said pin. The plate 25 is 110 provided at opposite portions with ears 27 through which screws may be applied for

fastening said plate to the casing 16, as shown in Figs. 2 and 7. The inner edges of the sleeve 20 abut against the inner wall 28 of the recess formed within the casing 5 of the rest, and said sleeve adjacent to its inner edges is formed with an annular shoulder 29 against which is applied a plate or disk 30 which serves to close that portion of the inner side of the sleeve 20 which in- 10 closes the drum 22 and tape 14. The disk 30 is stationary and the pin 21 extends through the same and is headed at its inner end exteriorly to the said disk. The disk 30 has cut in it a flexible or spring tongue 15 31, and this tongue is in engagement with the inner end of the pin 21 and carries at its outer portion a pin 32 which projects inwardly toward the drum 22. The drum 22 has an inner wall 33 in close proximity 20 to the disk 30, and said wall 33 is formed with a concentric series of recesses 34, any one of which may be engaged by the pin 32 for locking the drum 22 against rotation. The tension of the spring 24 acts to automatically 25 rotate the drum 22 in a direction to wind the tape 14 upon the exterior of said drum, and the purpose of the spring tongue 31 and pin 32 in coöperation with the recesses 34 in the drum 22 is to hold 30 said drum against rotation and the spring 24 under restraint. When the parts are in normal position, the locking pin 32 is projected into one of the recesses 34 and at such time the drum 22 is prevented from being rotated in either direction,—either to pay out the tape 14 or automatically rewind said tape upon said drum. When it is desired to withdraw the tape 14 outwardly from the rest, the operator will press inwardly on the knob 26 so as to force the spring tongue 31 outwardly in a direction from the drum 22 for the purpose of carrying its locking pin 32 from engagement with the drum, and thereupon and while 40 45 said pin is disengaged from the drum, the operator may pull outwardly on the tape 14 so as to extend such length of the same as may be necessary, after which the pressure on the knob 26 will be released and the pin 32 will pass into reengagement with one of the recesses 34 and lock the drum 22 against rotation, thus leaving a length of the tape 14 extended and the mechanism of the stop in such condition that the spring 24 will be 50 55 restrained from rewinding the tape upon the drum and the drum will be restrained from paying out any further length of the tape due to any outward pressure of the cello against the rest or stop 12 tending to push 60 said rest or stop forwardly in a direction from the chair 10.

The outer end of the tape or flexible connection 14 is connected with an eye or ring 35 which is secured by a swivel 36 to the 65 band or strap 15, the latter being simply a

straight strap provided with a suitable buckle 37 by which it may be looped around a leg of the chair 10, as shown in Fig. 1, or around other restraining means. In this instance it is necessary that the rest or stop 70 12 be held in predetermined relation to the chair 10 on which the player sits, and hence when the tape is extended and connected with the leg of the chair, the chair and the player sitting thereon will prevent the cello 75 from pushing the rest or stop 12 forwardly. The tape and its strap or band 15 serve as a means for restraining the stop or rest 12 against sliding movement on the floor in a direction from the player, or in other words 80 holds the rest or stop 12 in that predetermined position given to it for properly receiving the leg of the cello.

Within the casing 16 and leading from the chamber thereof through the tongue portion 85 18 is provided a slot 38 through which the tape 14 may travel and be kept in flat condition, as distinguished from becoming twisted, and the provision of the swivel 36 is to permit the strap or band 15 to be freely 90 handled and looped around the leg of a chair or other abutment without twisting the tape 14, which will preferably be of metal.

In addition to slitting or cutting the disk 95 30 to form the spring tongue 31, I preferably also slit or cut said disk on the arc of a circle, as at 39, to form a spring section in said disk to carry the tongue 31 and co-operate therewith in returning the pin 32 to 100 one of the recesses 34 in the drum 22 after inward pressure on the knob 26 has been released.

The operation of the mechanism constituting my invention has been so fully pointed out hereinbefore that it is believed that further description as to such operation is unnecessary. I do not limit my invention to the details of mechanism hereinbefore described otherwise than the appended claims 110 may require.

What I claim as my invention and desire to secure by Letters Patent, is:

1. A rest or stop of the character described, for a cello or the like, comprising a 115 body to rest on the floor and having a recess in its upper part to receive the depending leg of the cello, a rotary drum in said body, a tape wound thereon and extensible from said body, a spring for actuating said drum 120 to wind said tape thereupon, means for locking said drum against rotation in either direction, manually operative means for releasing the drum to permit the withdrawal of said tape, and means on the outer end of 125 said tape adapted to be engaged by means of restraint when said tape is extended from said body for preventing said body from sliding forwardly on the floor.

2. A rest or stop of the character de- 130

scribed for a cello or the like comprising a body to rest on the floor and having a rear-
wardly projecting tongue portion formed in
its upper surface with a recess to receive the
5 depending leg of the cello, a drum in said
body, a tape wound thereon and extensible
from said body, a spring for actuating said
drum to wind said connection thereupon,
means for locking said drum against rota-
10 tion in either direction, manually operative
means for releasing the drum to permit the
withdrawal of said tape, and means on the
outer end of said tape adapted to be engaged
by means of restraint when said tape is ex-
15 tended from said body for preventing said
body from sliding forwardly on the floor.

3. A rest or stop of the character de-
scribed for a cello or the like, comprising a
body to rest on the floor and receive the de-
20 pending leg of the cello, a rotary drum in
said body, a pin extending through said
drum and having an exposed head and hav-
ing limited sliding movement, a spring with-
in said drum and at one end connected there-
25 to and at the other end to said pin, locking
means connected with the end of said pin
and adapted to engage said drum and lock
the same against movement in either direc-
tion, a tape wound upon said drum and ex-
30 tensible from said body, and means on the
outer end of said tape adapted to be engaged
by means of restraint when said tape is ex-

tended from said body for preventing said
body from sliding forwardly on the floor.

4. A rest or stop of the character de- 35
scribed for a cello or the like, comprising a
body to rest on the floor and receive the de-
pending leg of the cello, a rotary drum in
said body, a pin extending through said
drum and having an exposed head and hav- 40
ing limited sliding movement, a spring with-
in said drum and at one end connected there-
to and at the other end to said pin, locking
means connected with the end of said pin
and adapted to engage said drum and lock 45
the same against movement in either direc-
tion, a tape wound upon said drum and ex-
tensible from said body, and means on the
outer end of said tape to be engaged by
means of restraint when said tape is extend- 50
ed from said body for preventing said body
from sliding forwardly on the floor, said
locking means comprising a spring tongue
carrying a locking pin and said drum hav-
ing at its inner end a series of recesses to be 55
respectively engaged by said locking pin.

Signed at New York in the county of New
York and State of New York, this 19th day
of August, A. D. 1916.
